PARTITION STUD STRUCTURE

William M. Goldsmith, Cincinnati, Ohio

Application October 31, 1938, Serial No. 237,816

7 Claims. (Cl. 72—115)

This invention is a continuation in part of my pending application Serial No. 193,564, filed March 2, 1938. The additional or new matter disclosed herein is to be understood as a carrying forward of the new and useful features disclosed in and divided from said copending application. It is also to be understood that various elements disclosed may be interchangeably employed with similar functioning elements in said copending application.

An object of the instant invention is to provide adjustable structural elements that may be readily assembled either in factories or assembly plants or on a job where same are to be installed, and which will readily adapt themselves to adjustment of the various parts thereof and fixation of such parts in various adjusted relationships.

Another object of the invention is to provide a device of the character indicated that is simple of construction, fabrication and assembly, and which may be readily secured in various adjusted positions by means of implements commonly and customarily available on jobs where such devices are used or installed.

Another object of the invention is to incorporate in structural elements customarily used in the building industries, the features of novelty and utility for attaining the indicated objectives.

These and other objects are attained by the means described herein and illustrated in the accompanying drawings, in which:

Fig. 1 is a fragmental elevational view of structural elements embodying the invention.

Fig. 2 is an elevational view of parts shown in Fig. 1 at right angle thereto.

Fig. 3 is a plan view of parts shown in Fig. 2.

Fig. 4 is a view similar to Fig. 1 showing a modified form of the invention.

Fig. 5 is an elevational side view of parts shown in Fig. 4.

Fig. 6 is a fragmental elevational view of one of the parts shown in Figs. 4 and 5.

Fig. 7 is a fragmental elevational view of a modified form of the invention.

Fig. 8 is a view similar to Fig. 6 and showing parts included in Fig. 7.

Fig. 9 is a sectional view on line 9—9 of Fig. 7.

Fig. 10 is a side view of a modified form of the invention, parts being broken away.

Fig. 11 is a sectional view on line 11—11 of Fig. 10.

Fig. 12 is a perspective view of an assembly of parts shown in Fig. 10.

Fig. 13 is an end view of a modified form of the invention.

Fig. 14 is a view of parts shown in Fig. 13, said parts being shown in a disconnected relationship.

Fig. 15 shows in elevation, a modified form of the invention.

Fig. 16 shows a plan view of parts shown in Fig. 15.

Fig. 17 shows a perspective view of parts shown in Fig. 18, and illustrating a modified form of the invention.

10 Fig. 18 is a plan view of parts shown in Fig. 17.

As explained in my said copending application Serial No. 193,564, the structural elements shown herein are intended for such uses as studding forming part of partition walls and the like.

15 Likewise, it is intended that the invention disclosed herein may embody any studding intended for both solid and hollow wall structures.

The invention as disclosed herein comprises a base or runner member 10, generally of inverted channel form, and which is adapted to be secured at intervals to a suitable floor 11 by appropriate attachment means such as nails 12. The base or runner member 10 is provided at intervals with slots or openings 13 in the base portion

20 14 of the runner and which are adapted to register with corresponding openings or slots 15 provided in the base 16 of a complementary inverted channel member 17 which may be referred to as the foot member of the stud base or support.

25 Preferably, the apertures 15 and 13 are oval or elongated and the elongations of the apertures 15 and the member 16 are preferably sufficient to permit positioning of the member 16 at any place longitudinally of the member 10 and yet have

30 registration of one or more of the apertures 13 and 15. A suitable key or locking member 18 is provided for insertion through registering openings 13 and 15 for locking or securing the members 10 and 17 in adjusted relationship. The foot

35 member 17 is preferably integral with the vertical leg 19 of the stud base or support. The leg 19 is preferably of channel iron formation and is adapted to slidably and adjustably receive the studding member 20.

40 As shown in Figs. 1 and 2, the vertical adjustment of the studding member 20 in the vertical leg 19 is effected by providing an elongated vertical slot or opening 21 in the base or web of leg 19 and into and through which opening there

45 projects a deformed portion 22 of the studding member 20. The deformed portion 22 is in the nature of an eye adapted to receive a fastening member such as a nail 23. The shank of the nail is adapted to extend on opposite sides of the eye 22 and to frictionally engage the base 24 of the

50 55 invention.

leg 19 on opposite sides of the slot 21 as well as to frictionally engage the under or inner surface of the eye or lug 22 formed on the studding member 20. In fabricating the indicated parts, the eye 22 is preferably so formed and shaped that in order to introduce the nail 23 into the eye and to cause it to assume the previously described position, the nail must be driven, by means of a hammer or similar implement, through the eye 22, whereby the nail or wedge member assumes a position in substantial parallelism with the webs of the channel bars constituting the adjustable or telescopic studding member. By so applying the holding means or nail 23, a substantial mounting of the studding member 20 upon the vertical leg 19 is effected. In other words, a driving fit is provided, and consequently, the frictional engagement of the nail shank 23 with the members 19 and 20 serves to provide a solid lock between the indicated parts. It is to be understood that the nail 23 and the eye 22 may be disposed at any angle that will attain the indicated relationship of parts.

Preferably the studding 20 comprises an integral lug 25 that is adapted to extend through the opening 21 and the free end of which is turned over the base 24 of the vertical leg 19 for avoiding separation of the studding member 20 and the leg 19 incident to handling thereof prior to mounting of said elements and fixation thereof by means of the holding means such as the nail 23. The assembly of the leg 19 and studding member 20 may be effected in any suitable manner, for example, either by turning the lug 25 over to the position shown in Fig. 1 after the parts have been assembled, and at which time, the lug 25 would extend substantially at right angle to the base 26 of the channel iron constituting the studding member 20 or the lug 25 may be given its final form as shown in Fig. 1, prior to assembly of the parts 19 and 20 and the leg 19 may be provided with a suitable slot incident to right angled turning of the lug 27 and which lug 27 is returned to a position coplanar with the base 24 of the leg 19 after the lug 25 has been passed through the referred to slot and the leg 19 and studding member 20 have been initially assembled.

In lieu of the key 18 shown in Figs. 1, 2, and 3 for mounting the inverted channel form foot of the stud base on the runner 10, any other suitable locking means may be employed. For example, any of the arrangements shown in my referred to copending application for attachment of a corresponding foot member to a corresponding runner may be employed.

In Figs. 4 and 5, such other attachment means embody a lug 50 struck upwardly from the base 51 of the U-shaped channel runner member 52. The foot member 53 of the stud base or support 54 is adapted to be positioned beneath the lug 50 in the manner taught in my referred to copending application. Likewise, similar lugs such as 50 may be employed, for example, as shown at 55, for securing the stud base 54 in position upon the runner. As shown in Figs. 4 and 5, the foot member is of channel iron structure and the opposite legs 56 of the foot 53 are disposed adjacent the inner faces 57 of the arms 58 of the channel iron runner 52. Thus, the stud base is secured against lateral shifting or movement. By reference to Fig. 5, it will be observed that sufficient of the horizontal arm members 56 of the foot 53 have been eliminated to accommo-

date the lower ends of the vertically disposed arms 58 of the channel iron vertical leg member 54.

The runner 51 is provided with suitable apertures 59 through which attachment means such as nails, may be passed for securing the runner upon a floor.

10 The means for adjustably securing the vertical stud member 60 to the vertical leg 54 of the stud base comprises an angularly disposed lug 61 formed from the web or base 62 of the channel iron 60. The lug 61 extends through and beyond an elongated slot 63 formed in the vertical leg member 54 and is perforated for receiving the shank 64 of a nail 65 which functions in the same manner as does the nail 23. The upper end of the elongated slot 63 is given such configuration, for example, as shown at 66, as will permit insertion of the lug 61 into and through the slot or opening 63 provided in the stud base 54.

25 Fig. 7 shows a variation of parts shown in Fig. 4 and as disclosed in Fig. 7, the lug 70 struck from the base 71 of the vertical leg 72 for permitting passage of the lug 73 through and beyond the lug 72, has been returned to coplanar position relative to the base 71, thus serving to preclude separation of the vertical leg 73 and the studding member 74.

30 It will be observed that when the invention, in the various forms disclosed herein, is embodied in structural elements of channel iron form or character, the positioning of the arms or legs of one channel immediately adjacent the arms or legs of a complementary and contacting channel member, effects a very simple and effective arrangement for restraining such members against lateral displacement or shifting. That is true regardless of whether the channel members, particularly the base portions thereof, are in the positions shown in Figs. 4 and 5 or whether they are in inverted positions as shown in Figs. 1, 2 and 3. The same observations apply in regard to the vertically disposed channel members.

35 While the invention has been disclosed herein as embodied in structural elements of channel shape or form, it is to be understood that the structural elements need not be of that specific character or form, and that it is contemplated that embodiment of the invention in structural forms of different shapes and character, will also include adequate lateral support for the structural elements, various forms of which are disclosed in my referred to copending application.

40 It will be observed that the relatively adjustable studding members such as 19 and 20 slidably overlap, at an end of each thereof, and that the relationship of the elongated slots, eyes, and lugs such as 25, and the overlapped legs or arms of the channel members 19 and 20, is such that the studding members cannot separate after they have been initially assembled, and that adjustment of the studding members is limited to directions, back and forth or longitudinally of the combined or assembled studding members. It will also be observed that the openings provided for the insertion of the clamping or wedging members such as nail 23 are forms of eyes, whether effected by a structure as shown at 22 or by perforating the lugs such as are shown at 61 and 73.

45 The key 18, as employed herein, functions as a wedge and accordingly may be used, together with equivalent registering slots, for adjustably securing vertical studding members such as 19

and 20. Likewise, an arrangement equivalent to the slot, eye, lug and nail shown in Fig. 1 may be used for adjustably securing studding bases to runners.

It is to be understood that studding is to be mounted at spaced intervals along the same runner, whereby to provide a plurality of aligned vertical supports or studding members to which lath may be secured, in the manner explained and intended in my said copending application, and in accordance with customary building practices, for example, as disclosed generally in such prior patents as Schirra 785,579 and Hill 975,426.

The opposed walls or edges 80, 81, 82 and 83 of the key 18 are preferably so related that when the key is inserted in aligned slots in a pair of channel iron members and then is turned so as to dispose the key transversely to said members, as shown in Fig. 3, the said key walls will bind or wedge the channel members securely together. That may be effected by slightly tapering the walls or edges relative to one another.

In a broad sense, the eye structure shown at 22 and the insertion thereof in the elongated slot 21, constitute a form of registering slots or apertures for the accommodation of a wedging or clamping means, which as shown in Fig. 1, is the nail 23.

In Figs. 10, 11 and 12, there is shown a rather wide channel iron 90 serving as a runner. The studding base 91 has its bottom or horizontal leg 92 positioned between the arms 920 and 93 of the runner, and such parts are so related that lateral shifting or movement of the studding base is precluded. The lugs 94 and 95 formed from the runner, serve to secure the studding base similarly as do similar lugs shown in Fig. 5. The vertical arm 96 of the stud base 91 is shown as being of a channel iron form, the arms 97 and 98 thereof cooperating with the spaced channel bars 99 and 100 of the main studding member 101, for slidably guiding the main studding, when adjustment thereof is desired. The channels 99 and 100 are secured together in spaced parallel relationship by means of strap 102. Bolts 103 extending through the central portion or web of strap 102 also extend through elongated slots 104 in the base of the channel member 96. Nuts used with the bolts are employed to clamp the various parts in final adjusted positions. Prior thereto, the loose assembly of the bolts and nuts, with the other parts of the device, permit ready adjustment or sliding movement of the main studding longitudinally and vertically of the studding base. In hollow partitions, using such studding, lath may be wired to the channels, the spacing of the channels readily permitting such method of attachment.

In Figs. 13 and 14, the studding base 110 and main studding member 111 are shown as channel irons, the one being slidably received in the other. An elongated slot 112 in the base receives the bolt 113 carried by member 111 and the nut 114 associated with the bolt may be of such size that the nut is prevented from turning, thus permitting ready clamping of the parts upon one another by means of an ordinary screw driver. The bottom or horizontal leg 115 may be secured to the runner 116 in any of the various manners disclosed herein for attaching a studding base to a runner.

In the form shown in Figs. 15 and 16, a pair of channel irons 201 and 202 are secured to strap or connector plate 203, for example by welding. Spot welding is indicated at 208. The eye 204 is formed in plate 203 for cooperation with nail 205

and the area of studding base 206 adjacent to the slot 207 in said base 206 as do corresponding parts in Fig. 1.

5 The bottom member or base 209 of the angularly disposed studding base 206 may have its opposite ends 213 and 214 received between the lugs 240 and 241 provided on the runner 242 as disclosed and explained in greater detail in my said copending application.

10 In Figs. 17 and 18 the ends 250 and 251 of base 252 of studding member 306 are introduced beneath the upwardly pressed pocket or socket members 211 and 212 by a turning movement of the member 306 relative to runner 253. The free edges of the socket members are spaced at a sufficient distance from the upper face of the runner to permit such assembly. The fit of such parts may be sufficiently snug to securely anchor the member 306 on the runner 253. If desired, lug 217 may be provided as an added means for locking the parts 306 and 253 in assembled relation.

15 From the foregoing it is readily evident that substantial clamping of parts is effected by the structures shown in Figs. 15 to 18 inclusive, similar to what is accomplished in the other forms of the invention.

20 It is to be understood that the member 206 may be of channel iron shape in cross section, or may comprise a flat piece of material having the base 209 thereof turned at an angle to the body or vertical portion thereof.

25 In various forms of the invention, for example, Fig. 4 and Fig. 7, the lugs such as 61 and 73 may be twisted somewhat, to avoid separation of the studding members, after assembly thereof, thus obviating use of such lugs as 70 for attaining the same objective.

30 What is claimed is:

1. Partition studding of the class described comprising a pair of relatively movable studding members for adjustment longitudinally of one another, one of said members having an elongated slot extending longitudinally thereof, the other of said members having an eye formed thereof, said eye extending through the slot in the first mentioned member and being adapted for movement longitudinally of said slot and a wedge member extending through the eye and frictionally contacting the first mentioned member on opposite sides of the said slot, whereby to secure said studding members together in determinable positions longitudinally of one another.

35 2. In a device of the class described the combination of a pair of overlapping channel irons, each having a slot in one registering with a slot in the other, the slot in one of said channel irons being elongated and the material adjacent the slot in the other of said channel irons extending into and adapted to be slid longitudinally of the elongated slot in the other channel member, and wedge means cooperating with the registering slotted portions of said channel irons for fixedly securing the overlapping portions of the channel irons to one another.

40 3. In a device of the class described the combination of a pair of relatively movable members having registering openings therein, one of said openings being elongated and the material about said other opening extending into and being slidably longitudinally of said elongated opening, and means extending through said openings and having the opposite ends thereof disposed in contact upon the same face of one

of said members and having its intermediate portion disposed in said openings for clamping the members together in fixed position relative to one another.

4. In a device of the class described the combination with a runner member having upwardly struck lugs thereon, said lugs extending in opposite directions whereby to provide slots or sockets opening in part toward one another and opening in part in opposite directions, and a 10 studding base mounted on said runner and having a base portion engaging said runner and having its opposite ends received in said sockets.

5. In a device of the class described the combination with a runner member having upwardly 15 struck lugs thereon, said lugs extending in opposite directions whereby to provide slots or sockets opening in opposite directions, a studding base mounted on said runner and having a base portion engaging said runner and having its opposite ends received in said sockets, and means for holding said base portion against movement whereby to lock said ends of the base in said sockets and to also prevent vertical separation of said base from said runner member.

6. In a device of the class described the combination of a pair of overlapping channel irons, each having a slot in one in operating relation

5 with a slot in the other, the slot in one of said channel irons being elongated, the other channel iron having a lug formed therefrom, said lug extending through said elongated slot and being turned on itself and extending over the other channel iron adjacent said elongated slot in said other channel iron, and means cooperating with said slots and having contact with both said channel irons for fixedly securing the overlapping portions of the channel irons to one another.

7. Partition studding of the class described comprising a pair of elongated studding members having an end of one slidably overlapping an end of the other, one of said members having an elongated opening extending longitudinally of said member, the other member carrying an integral lug extending through said elongated opening and slidably projecting over a portion of said member having said elongated opening, and means extending through said lug carrying member and having selectable contact with said other member along and adjacent said elongated opening in said one member for fixedly securing the overlapping portions of said studding members to one another.

WILLIAM M. GOLDSMITH.
